J. WHITELEY

Des. 78,701

AMUSEMENT BUILDING FRONT

Filed Feb. 11, 1929

Inventor:
James Whiteley,
20 Hippay & Kingsland,
His Attorneys.

UNITED STATES PATENT OFFICE.

JAMES WHITELEY, OF OLCOTT, NEW YORK.

DESIGN FOR AN AMUSEMENT BUILDING FRONT.

Application filed February 11, 1929. Serial No. 30,010. Term of patent 14 years.

To all whom it may concern:

Be it known that I, JAMES WHITELEY, a citizen of the United States, residing in Olcott, county of Niagara, and State of New York, have invented a new, original, and ornamental Design for Amusement Building Front, substantially as shown in the accompanying drawing, in which

Fig. 1 is a front elevation of an amusement building front showing my new design.

Fig. 2 is a side elevation of the front portion of the building.

I claim:

The ornamental design for an amusement building front, substantially as shown.

JAMES WHITELEY.
